UNITED STATES PATENT OFFICE.

WALTER HALLOWELL DONALDSON, OF SAN FRANCISCO, CALIFORNIA.

COMPOUND ENGINE.

SPECIFICATION forming part of Letters Patent No. 333,507, dated January 5, 1886.

Application filed March 31, 1885. Serial No. 160,829. (No model.)

To all whom it may concern:

Be it known that I, WALTER HALLOWELL DONALDSON, a resident of San Francisco, State of California, have invented a novel and 5 useful Compound Engine; and I hereby declare that the following is a full, clear, and exact description of the same, reference being had to the accompanying drawings.

My invention relates to a novel construction 10 of a compound engine having an intermediate reciprocating high-pressure cylinder, long connecting rods, and only one gland.

The following description fully explains 15 the nature of my said invention and the manner in which I proceed to construct, apply, and operate the same, the accompanying drawings being referred to by figures and letters.

Figure 1 represents a vertical section through 20 center of engine, showing the engine on half-stroke. Fig. 2 is a plan view of the intermediate valve. Fig. 3 represents an elevation of connecting-rod. Fig. 4 is a plan view of engine, showing high-pressure valve. Fig. 5 represents a vertical section of engine in line 25 of crank-shaft, showing engine on top center. Fig. 6 is a plan view of exhaust-valve. Fig. 7 is a plan view of high-pressure valve. Fig. 8 is a plan view of engine. Fig. 9 represents 30 a cross-section of high-pressure cylinder and low-pressure piston, showing the connecting-rods and branch lubricating-pipes. Fig. 10 represents a section of high-pressure cylinder and low-pressure piston, showing device 35 for lubricating wrist-pins. Fig. 11 is a plan view of low-pressure piston, showing branch pipes for lubricating wrist-pins.

Referring to Fig. 1, the stationary high-pressure piston is marked *a*; high-pressure 40 cylinder and low-pressure piston, cast in one piece, *b*; low-pressure cylinder, *c*, bolted to base. Water-tight crank-case is marked *d* in square base of engine-frame; connecting-rods, *e*; high-pressure-cylinder valve, *f*; intermediate 45 valve, *g*; exhaust-valve, *h*; high-pressure-valve stem, *i*; square steel valve-stem, *i*^x; bevel gear-wheels, *j*; stuffing-box and gland, *j*^x; steel bushing, *k*; annular chamber, *m*; pipe to condenser or atmosphere, *n*; steam-supply pipe, *o*; auxiliary valve, *p*; wrist-pins for connecting-rods, *q*; working-barrel, *r*, and stationary plunger, *s*, of lubricating-pump; oil-discharge 50

branch pipes, *t*; man-hole plate, *y*, and crank-case or square base of engine-frame disks, *z*.

Referring to Fig. 2, the intermediate valve 55 is marked *g*, and square hole in same *l*.

Referring to Fig. 3, the connecting-rods are marked *e*.

Referring to Fig. 4, the high-pressure cylinder-valve is marked *f*, and square hole in 60 same *l*.

Referring to Fig. 5, the stationary high-pressure piston is marked *a*; high-pressure cylinder and low-pressure piston, in one piece, *b*; low-pressure cylinder, *c*, bolted to base; 65 water-tight crank-case, *d*; connecting-rod, *e*; high-pressure-cylinder valve, *f*; intermediate valve, *g*; exhaust-valve, *h*; high-pressure-valve stem, *i*; square steel valve-stem, *i*^x; bevel gear-wheels, *j*; stuffing-box and gland, *j*^x; steel 70 bushing, *k*; square hole in valves, *l*; annular chamber, *m*; wrist-pins for connecting-rods, *q*; working-barrel, *r*; and stationary plunger of lubricating-pump, *s*; oil-discharge branch pipes, *t*, and crank-case disks, *z*.

Referring to Fig. 6, the exhaust-valve is 75 marked *h*, and square hole in same *l*.

Referring to Fig. 7, the high-pressure cylinder valve is marked *f*, and square hole in same *l*.

Referring to Fig. 8, the crank-case disks are marked *z*.

Referring to Fig. 9, the high-pressure cylinder and low-pressure piston, in one piece, is marked *b*; wrist-pins for connecting-rods, *q*; 85 working-barrel of lubricating-pump, *r*; oil-discharge branch pipes, *t*, and oil-holes in upper end of connecting-rods, *u*.

Referring to Fig. 10, the high-pressure cylinder and low-pressure piston, in one piece, is 90 marked *b*; connecting-rods, *e*; water-tight crank-case, *d*; working-barrel, *r*, and stationary plunger of lubricating-pump, *s*; oil-discharge branch pipes, *t*; oil-holes in upper end of connecting-rods, *u*; suction-openings for oil in lubricating-pump, *r*; ball-valves, *w*, and valve-seats, *x*, in working-barrel, and stationary plunger of lubricating-pump and man-hole plate, *y*. 95

Referring to Fig. 11, the high-pressure cylinder and low-pressure piston, in one piece, is 100 marked, *b*; oil-discharge branch pipes, *t*, and oil-holes in upper end of connecting-rods, *u*. The high-pressure piston *a* is stationary, being cast with or bolted to a base. The high-press-

ure cylinder and low-pressure piston are cast in one piece, *b*, and the low-pressure cylinder *c* is bolted to a base, as shown. The base of the engine column or frame is a water-tight 5 crank-case, *d*, and affords a means for lubricating the cranks and valve-gear. The motion of the low-pressure piston is transmitted to the cranks by means of two connecting-rods, *e*. There are three valves—namely, the high-pressure, *f*, intermediate, *g*, and exhaust, *h*. These valves are metal disks, with radial openings of suitable size, revolving against the piston heads or followers, the heads or followers having openings cut in them corresponding to 10 the holes *l* in the valves. The valves are held to their places by steam-pressure on the under side. Motion is imparted to the high-pressure valve *f* by bevel gear-wheels *j*, the one attached on the lower end of the valve-stem *i* 15 engaging with one of equal diameter on the driving-shaft. The wrist-pins *q* of the upper ends of the connecting rods are lubricated by a device shown in Fig. 10, consisting of a pump, made of brass or other metallic tubing, one tube forming a stationary plunger, *s*, secured to the crank-case *d*, the other tube fitting it closely and forming the working-barrel *r* of the pump. The stationary 20 tube or plunger has openings *v* at its base, for the admission of the oil and water, by which it is surrounded, and at the upper end of the tube there is a ball-valve, *w*, made of metal or rubber, and a valve-seat, *x*. The other tube or working-barrel is tapped into the low-pressure piston, and is provided with two 25 branch pipes, *t*, leading to points directly above the oil-holes *u*, in the connecting-rod heads. This tube is also provided with a ball-valve, *w*, and valve-seat *x*. I dispense 30 with stuffing-boxes and glands, only one, *j*, being employed in my compound engine, thereby greatly reducing friction and avoiding the time and expense required to adjust and keep them in condition. The stem *i* of 35 the high-pressure valve *f* is formed of steel tubing with a steel bushing, *k*, welded into the top end, having a square hole in it. The intermediate valve, *g*, has a stem of square section running freely into the steel bushing, 40 permitting a vertical motion, and at the same time receiving a rotary motion from the high-pressure-valve stem. The square stem of the intermediate valve continues above the valve high enough to pass through a square hole, *l*, 45 in the exhaust-valve *h*, and rotating it. The length of the square valve-rod *i* above and below the intermediate valve will be governed by the length of the stroke of the piston, its length not permitting it to leave the bushing 50 *k*. The exhaust-valve opens into an annular chamber, *m*, on top of the low-pressure cylinder, and thence by the pipe *n* to the condenser or to the atmosphere. Steam is supplied by the supply-pipe *o* to the stationary high-pressure 55 piston *a*. It is also introduced into the low-pressure cylinder *c* from the supply-pipe by an auxiliary valve, *p*, which is to be used

only when the engine is brought to a stop on the downstroke. As the high-pressure valve *f* is only open on the upstroke, it is necessary 70 to admit enough live steam on top of the low-pressure piston *b* to start it on the downstroke, when the regular motion of the valves will take place. The crank-shaft boxes are cast to disks *z*, which are bolted to the crank-case *d*. In the crank-case there is a man-hole 75 covered with a plate, *y*.

The operation of the lubricating device is as follows: The upstroke of the low-pressure piston draws the working-barrel *r* of the pump 80 up a distance equal to the stroke of the engine, creating a vacuum, into which the oil and water rise through the valve-opening. On the downstroke the valve *w* seats, and the water and oil are forced outward into the 85 branch pipes *t*, and thence through the openings over the oil-holes *u* of the connecting-rod.

Having thus fully described my invention, what I claim, and desire to secure by Letters Patent, is—

1. In a compound engine, the combination, 90 with the stationary low-pressure cylinder and the stationary high-pressure piston, of the portion *b*, forming both the low-pressure piston and the high-pressure cylinder, lying and working between the two first-named parts, and provided with connections for the rods *e*, substantially as set forth.

2. In a compound engine, the combination, 100 with the stationary high-pressure piston, combined reciprocating high-pressure cylinder and low-pressure cylinder, and the stationary low-pressure cylinder, of the rotating high-pressure valve *f*, located in high-pressure piston, rotating intermediate valve, *g*, in the combined cylinder and piston, and the rotating 105 exhaust-valve *h* in the low-pressure cylinder, and means, substantially as described, for imparting a rotary motion to said valves, as set forth.

3. In a compound engine, the combination, 110 with the two pistons and cylinders, as described, of the valves *f*, *g*, and *h*, located as shown and described, and the shaft *i*, and suitable gearing for rotating valve *f*, and non-circular spindle *i*, for rotating valves *g* and *h*, connected with shaft *i*, as set forth.

4. The combination, with the water-tight crank-case, of a pump having the tube or stationary plunger *s* and the tube or working-barrel *r*, both of said tubes being provided 120 with ball-valves and valve-seats, as set forth.

5. The combination, with the water-tight crank-case, of a pump connected to a reciprocating part of the engine, whereby lubricant 125 may be drawn from the case to the working parts of the engine, as set forth.

In testimony whereof I have hereunto set my hand and seal.
